UNITED STATES PATENT OFFICE.

WILLIAM BUCKHANAN WARE, OF MEMPHIS, TENNESSEE, ASSIGNOR OF ONE-HALF TO
ANDREW T. MADRA, OF MEMPHIS, TENNESSEE.

SAMPLING-MACHINE.

1,274,962.

Specification of Letters Patent. Patented Aug. 6, 1918.

Application filed May 11, 1917. Serial No. 167,915.

To all whom it may concern:

Be it known that I, WILLIAM BUCKHANAN WARE, a citizen of the United States, and a resident of Memphis, in the county of Shelby 5 and State of Tennessee, have invented a new and Improved Sampling-Machine, of which the following is a full, clear, and exact description.

The invention has for its object to provide 10 a cheap and efficient sampling machine which will automatically take a uniform and average sample of any powdered or granular material.

Additional objects of the invention will 15 appear in the following specification, in which the preferred form of the invention is disclosed.

In the drawings similar reference characters denote similar parts in all the views, in 20 which—

Figure 1 is a sectional view on the line 1—1 of Fig. 3;

Fig. 2 is a side elevation illustrating the sampling machine;

Fig. 3 is a sectional view on the line 3—3 of Fig. 1; and

Fig. 4 is a plan view of Fig. 2.

By referring to the drawings it will be seen that the sampling machine is used in 30 connection with a conveyer 5 which is disposed horizontally, and which has a bottom 6 with an opening 7. The top 8 of the sampling machine has an opening 9 with which the opening 7 in the bottom 6 of the conveyer 35 communicates. Rotatably mounted in the chamber 10 in the sampling machine there is a sampler-wheel 11, this sampler-wheel 11 being secured to a shaft 12 journaled in bearings 13 secured to the side of 40 the sampling machine. The top 8 of the sampling machine at its opening 9 converges downwardly as illustrated at 14, to the sides and periphery of the sampler-wheel 11, so that this sampler-wheel 11 will serve 45 to close the opening 9 and prevent the material which is passing through the conveyer 5 from falling therethrough. The sampler-wheel 11 is provided with a pocket 15 having an end 16 which is disposed substantially 50 radially, and a bottom 17 which is disposed substantially at right angles to the end 16. When the sampler-wheel 11 is rotated in the direction indicated by the arrow in Fig. 1 of the drawings, the pocket will receive 55 material falling through the openings 7 and

9, and will deposit this material in a box 18 at the bottom of the sampling machine. Journaled in bearings 19 in the top 8 of the sampling machine, there is a shaft 20, to which agitators 21 are secured, these agitators 21 serving to prevent the material passing through the openings 7 and 9 from becoming clogged. 60

At the bottom of the box 18 there is a drawer 22 which serves to permit the ready 65 removal of some of the samples which have been collected and have been deposited therein. As a means of mixing the material which is collected in the drawer 22, I provide agitators 23 which are secured to a 70 shaft 24 journaled in bearings 25 secured to the sides of the sampling machine.

In bearings 26 at one side of the sampling machine there is journaled a shaft 27 to which a pulley 28 is secured, a gear 29 being 75 also secured to the shaft 27 which meshes with a gear 30 secured to the shaft 12 and with a gear 31 secured to the shaft 20. There is also secured to the shaft 12 a sprocket wheel 32 which is connected with a 80 sprocket wheel 33 secured to the shaft 24 by means of a sprocket chain 34. Openings 35 are made in the walls of the sampling machine at and below the sampler-wheel 11, and glass panes 36 are secured in these 85 openings so that the operator may at all times observe whether or not the samples are being taken of the material passing through the conveyer 5. The top 8 of the sampling machine has bracket arms 37 which 90 are secured to opposite sides of the conveyer 5.

Having thus described the invention, I claim as new and desire to secure by Letters Patent:

1. In a sampling machine, a conveyer having a bottom with an opening intermediate its ends, means for advancing material longitudinally of the bottom of the conveyer, a sampler wheel rotatably mounted 100 below the opening, means connecting the conveyer bottom around its opening with the sampler wheel at its periphery, the sampler wheel having a pocket in its periphery for the purpose specified. 105

2. In a sampling machine, a conveyer having a bottom with an opening intermediate its ends, a sampler wheel rotatably mounted below the opening, means connecting the conveyer bottom around its opening 110

with the sampler wheel at its periphery, the sampler wheel having a pocket in its periphery, a box disposed below the sampler wheel, a drawer in the box and an agitator 5 in the box for mixing the material collected in the drawer.

3. In a sampling machine, a conveyer having a bottom with an opening intermediate its ends, a sampler wheel rotatably 10 mounted below the opening, means connecting the conveyer bottom around its opening with the sampler wheel at its periphery, the sampler wheel having a pocket in its periphery, a box disposed below the sampler 15 wheel, a drawer in the box, an agitator in the box for mixing the material collected in the drawer, an agitator in the opening in the bottom of the conveyer, and means for operating the sampler wheel and the 20 two agitators synchronously.

4. In a sampling machine, a member having an opening, a sampler wheel rotatably mounted with its periphery engaging the member at the opening to close the latter, 25 the sampler wheel having a pocket in its periphery, one end of which is disposed substantially radially relative to the axis of the sampler wheel, the bottom of the pocket being disposed substantially at right 30 angles to the said end and extending to the periphery of the sampler wheel.

5. In a sampling machine, a member having an opening, a sampler wheel rotatably mounted with its periphery engaging the

member at the opening to close the latter, 35 the sampler wheel having a pocket in its periphery one end of which is disposed substantially radially relatively to the axis of the wheel, the bottom of the pocket being disposed substantially at right angles to the 40 said end and extending to the periphery of the sampler wheel, and means to rotate the sampler wheel in a direction where the bottom of the pocket at the periphery of the sampler wheel will first pass the opening 45 in the member.

6. In a sampling machine, a member having an opening, a sampler wheel rotatably mounted with its periphery engaging the member at the opening to close the latter, 50 the sampler wheel having a pocket in its periphery, an agitator in the opening in the member, and means to operate the agitator and the sampler wheel.

7. In a sampling machine, a conveyer 55 having a bottom with an opening intermediate its ends, a sampler wheel rotatably mounted below the opening, means connecting the conveyer bottom at its opening with the sampler wheel at its periphery to close 60 the opening, the sampler wheel having a pocket in its periphery, a box disposed below the sampler wheel, a drawer in the box, an agitator in the box for mixing the material collected in the drawer, and means to 65 operate the agitator and the sampler wheel.

WILLIAM BUCKHANAN WARE.
